SHIRT BOARD

George Frederick Hiss, Los Angeles, Calif.

Application September 19, 1929, Serial No. 393,696

13 Claims. (Cl. 223—71)

This invention relates to a one piece shirt board adapted for use in shirt factories and laundries and for possible other purposes.

An object of the invention is to provide a one piece shirt board which is cut in such a manner as to adapt it for folding so that when folded it will overlie both the inside and outside of a shirt so that the shirt will be maintained in a rigid, smooth condition in which it is well protected both at the front and back and may be conveniently handled without likelihood of becoming soiled or disarranged.

Another object of the invention is to provide a shirt board upon which the shirt may be put in place by an easy folding operation and from which it may be as readily removed. The operation of folding and unfolding is aided by the fact that it is unnecessary to use pins or other fastening devices to hold the shirt in place upon the board.

Still another object of the invention is to more securely retain a shirt in place in its smooth folded position upon the board and to provide ready access to the shirt so that it may be quickly removed by a single operation.

Among other objects and advantages of the invention is the provision of means whereby the shirt may be held and removed from the board in such a manner that it is in position to insert the collar button; improved means for securely holding the sleeves in place without the use of pins or other fastening devices; elimination of side play of the shirt when in place upon the board, and in general to improve upon devices of this class with respect to low cost of manufacture and general convenience in use. Owing to the extraordinarily low cost at which the appliance may be manufactured and the provision of suitable space thereon when in use it is adapted to be used advantageously as an advertising device.

An important object is to provide a self-contained shirt board adapted to have a shirt folded thereon, and to provide novel means on said board whereby such board may be folded so as to partially cover the shirt on its front and back and to encircle the shirt to prevent accidental side movement of the shirt on the shirt board.

A still further object is to provide a novel shirt board whereby the shirt will be held upon the board and the sleeve retained thereon without other means than that contained on the board itself.

An object is to provide a novel, simple, shirt board that may be used by laundries and also used by factories or others desiring to fold the shirt in what is termed a "factory fold".

Other objects, advantages, and features of invention may appear from the accompanying drawing, the subjoined detail description, and the appended claims.

Referring to the accompanying drawing which illustrates a preferred embodiment of the invention,

Figure 1 is a front plan view of the device with a shirt mounted thereon in an approved folded condition, the appliance being shown in the form 10 generally used by laundries.

Fig. 2 is a rear plan view of the appliance and shirt positioned with respect to each other as shown in Fig. 1.

Fig. 3 is a rear perspective view of the board and shirt showing an intermediate step of the operation of mounting the shirt upon the board. A part of the shirt is broken away to contract the view.

Fig. 4 is a front plan perspective view of the shirt mounted upon the board and folded to a 20 form or size generally used by factories or for traveling purposes.

Fig. 5 is a plan view of the complete board, the same being in the extended position, showing the various flaps and foldable elements cut preparatory to being arranged into position for use.

Referring in detail to the drawing, the shirt board 7 is desirably made of cardboard, being constructed in a single rectangular piece having a body portion 8, nearer one end than the other of 30 which the board is provided with a transverse folding line or line of flexure 9, thereby marking off from said body portion 8 an outside flap 11 and an inside flap 12.

Said inside flap 12 is separated from said outside flap 11 by a symmetrical cut 14 which as shown in the drawing, is outcurved at 15 toward the adjacent end of the shirt board and which is provided with an indentation 16 at each side near its base, the ends of said cut terminating at 40 said folding line 9.

Said flap 12 will, at times, be referred to as the main flap in order to distinguish it from the auxiliary flap 20, and the small inner flap 21, both the latter flaps lying within the flap 12 and having their bases terminating at said line of flexure 9.

Said inside flap 21 is formed by and between two similar side cuts 22, these cuts preferably being slightly separated at the mid-width of the flap by an uncut area 23 which may readily be broken through to free said flap 21 for use.

The auxiliary flap 20 lies between the main flap 12 and the inner flap 21. Said auxiliary flap is separated from the main flap 12 by two similar

cuts 25 which are preferably slightly separated at 26 at the mid-width of these flaps. This uncut area 26 is readily broken through by the fingers to free flap 20. The cuts 25 are so shaped as to provide the auxiliary flap 20 with an ear 20c at each side thereof and also to provide the base portion of this flap with two limbs 27 between which the inner flap 21 is located. Said inner flap 21 is adapted to engage and retain in place 10 the collar band portion of a shirt.

The main flap 12 has cut therein two transversely extending oppositely directed finger-like flaps or ears 30. The free ends of these last flaps are directed toward each other, being slightly separated from each other at the mid-width of the board and their bases terminating at lines of flexure 31 which are located near the outer sides of the main flap. These finger flaps 30 when extended outwardly, are each of them sufficiently long to extend beyond the edge portions of the board and to have their terminal portions bent back a considerable distance upon the opposite face thereof.

In addition to the flaps which have thus far been enumerated the board is provided, near the flexure 9 and on the side thereof opposite to the main flap 12, with the transversely spaced oppositely disposed longitudinal straight cuts 35 each of which is joined at one end by an outwardly directed curved cut 36, thus forming similarly shaped locking flaps or ears 37.

Also, at about the mid-length of the board there is cut into each side thereof a cut 40 having the form of a compound curve and which, with regard to its general direction, is inclined from the edge of the sheet toward the ears 37 or the line of flexure 9.

The operation of mounting the shirt upon the board is as follows: The shirt is placed upon a table top or any suitable support T with the front or bosom portion thereof downward or lying directly upon the support. The shirt board is then laid upon the shirt lengthwise thereof, at substantially the mid-width of the shirt and, if the shirt is of the type illustrated in the drawing, the inside flap 21 is pushed out so as to free the uncut area 23 and flap 21 is then inserted in the collar band *a* in the usual space provided therein to receive the back collar button. Then the two side portions of the shirt that extend beyond the sides of the board are folded over the board toward each other until they occupy the position illustrated in Fig. 3. The sleeves of the shirt are then brought into position so that their shoulder portions are slipped under the flaps or ears 37 (see Fig. 3) after which the flaps 37 are pinched into their respective openings and thereby lock the sleeves upon the board, the sleeves are then folded in any desired manner, preferably within the confines of the body portion 8. The tail or skirt portion of the shirt is then folded upon the body portion 8, and then the inside flap 12 and the outside flap 11 are folded in opposite directions so that they respectively engage or lie against the back and front of the shirt as mounted upon the board. The transversely extending flaps 30 are then pushed out of the main flap 12 toward the longitudinal sides of the shirt board and the terminal portions *b* of said flaps 30 are then bent around the edge of the shirt and board and over the flap 11 and are then bent upon themselves so that the extreme terminal portion thereof will lie underneath the flap 11. The character of cardboard that is used provides sufficient rigidity to the flaps 30 so that they will of

themselves be retained in locking position without requiring the use of auxiliary means.

From the foregoing it will be seen that the opening in flap 11 provided by cutting out and removing flap 12 therefrom, is large enough to receive the neck portion of any standard size shirt whether constructed with a collar band or collar attached. The flaps 11, 12, and 30 are so proportioned relative to each other that the flaps 30 easily encircle the edge of the shirt board and are received in the opening provided by the flap 12. This construction eliminates the necessity of other shirt encircling means and also prevents the shirt from being accidentally displaced sideways upon the board after all the elements are connected together.

If a "factory fold" is desired, the lower portion c of the shirt and board is merely tucked under the flap 11 as shown in Fig. 4.

The opening in flap 11 provided by removing flap 12 therefrom is also so proportioned that when a shirt with collar attached is mounted upon my board, the tabs or ears of the collar will be received between the body of the shirt and the underside of flap 11 so as to retain them in place. This is not illustrated as it is believed apparent to those skilled in the art.

When it is desired to remove the shirt from the board, the shirt and board are grasped in the hand as though to insert the back collar button after which the flap 12 and fingers or flaps 30 are released in any suitable manner, or the shirt tail or skirt withdrawn from under the flap 12, and by pulling upon the sleeves, they are unlocked from the ears 37 and the sides of the shirt board at the upper portions thereof are permitted to move toward each other by reason of the compound cuts 40, permitting the fingers or flaps 30 to be released from locking engagement with flap 11 and thereby permitting the shirt to fall open and free from the shirt board.

When a shirt with collar attached is desired to be mounted upon my shirt board, instead of using the flap 21 for co-operation with the collar band as heretofore described, the flap 20 is used by breaking the uncut area 26 and such flap is inserted in the collar. The use of the flap 20 eliminates the necessity of a separate cardboard strip that is now used by many laundries and by cutting the sides of the flap 20 as shown in Fig. 5, the collar, if desired, may be folded flat in a manner that will be apparent.

I claim:

1. A shirt board having a transverse folding line and a flap cut from said board and having its base located substantially at said folding line, said flap being foldable lengthwise of the board upon one face thereof and the uncut portion of the board from which said flap is cut being reversely foldable along said folding line, upon the opposite face thereof, and means cut out from said flap and adapted to extend over the edges of said board and to connect said flap and the said uncut portion when said flap and uncut portion are moved to folded positions.

2. A shirt board having a transverse folding line which is located nearer one end of the board than the other thereby dividing the board into a long and a short end portion, and a flap cut from the short end portion of said board and having its base located substantially at said folding line, said flap being foldable down upon one face of said board and the remainder of said short end portion of the board being foldable down upon

- the opposite face thereof and means cut out from said flap adapted to extend over the edges of said board and to connect said flap and the said short end portion when said flap and short end portion are moved to folded positions.
- 5 3. A shirt board comprising a flat elongate body portion having a transverse folding line; a main flap having its base located substantially at said folding line and foldable down upon one face of said body portion; an auxiliary flap cut out within the outline of said main flap and having its base portion located substantially at said folding line and foldable down upon the other face of said body portion, said auxiliary flap when 10 folded upon said body portion leaving a recess in said main flap and through which recess the collar of a shirt mounted on said board will extend when said main flap is folded upon the opposite face of said body portion.
- 15 4. A shirt board having at one end a cut out portion forming a main flap adapted to be folded upon the body portion of said shirt board, and a transversely foldable flap cut out within the outlines of said main flap, said transversely foldable flap being of such length and so positioned as to be foldable over and around an edge portion of said board and then have its terminal portion hooked around the edge of the opening formed by the cutting out of said main flap.
- 20 5. A shirt board having two flaps which are extensible in opposite directions into positions wherein they project beyond edge portions of the board, said board having also a foldable end portion with an opening therethrough which is opposite to said flaps when said end portion is in the folded position, the end portions of said flaps being adapted at such time to be folded inwardly from their extended position and hooked around opposite edges of said opening, to retain said 25 end portion of the board in the folded position.
6. A shirt board comprising a body portion having cuts therein adjacent an end thereof, said cuts forming tabs adapted to leave an opening into which the sleeves of a shirt are adapted to be retained by said tabs, and a flap at the same end of the board adapted to fold down upon one face of said board to hold in place the neck portion of a shirt, the width of said board being sufficiently restricted to allow a shirt folded along the mid- 30
- 45 width of the garment to extend across both sides of said board.
7. A shirt board comprising a body portion and a foldable portion at one end thereof; a main flap member cut out of said foldable portion, said 45 main flap and the remainder of the foldable portion being adapted to be folded upon opposite sides of said body portion; and means connected to said main flap adapted to overlap the edges

5 of said body portion and to secure said main flap and foldable portion together.

8. A shirt board comprising a body portion having a cut therein along opposite sides in the form of a compound curve; flaps connected to one end of said body portion and being adapted to be folded upon opposite sides of said body portion; and means connected to one of said flaps adapted to encircle the edges of said body portion and to be secured in flap locking position with the other of said flaps.

9. A one piece rectangular shirt board having a body adapted to have a shirt mounted on and folded about said body so that said body will be positioned inside the folds of said shirt; and flaps extending from one end of said body adapted to be folded about the shirt mounted on said body so that said end flaps will be positioned on both outsides of said shirt; and locking flaps cut out of and integral with one of said end flaps, said locking flaps adapted to encircle the edges of said board and to engage the other of said end flaps to retain said shirt and folded end flaps of said board compact.

10. A shirt board comprising a body portion having cuts therein along opposite sides, each in the form of a compound curve; and locking flaps cut out of said body portion adapted to form retaining means for the sleeves of a shirt mounted upon said board.

11. A shirt board having a transverse folding line, thereby dividing said board into a body portion and a flap portion, said flap portion having separated therefrom an inside flap, and said inside flap having cut out therefrom a small inner flap.

12. A shirt board having a transverse folding line, thereby dividing said board into a body portion and a flap portion, said flap portion having separated therefrom an inside flap, said inside flap having cut out therefrom a small inner flap; and flaps cut out from said inside flap and adapted to be extended in opposite directions to project beyond and encircle the longitudinal edges of said body portion.

13. The combination of a shirt board and a shirt folded around said board, said shirt board comprising a substantially elongate rectangular body portion; and a member extending upwardly from one narrow end of said board at approximately the longitudinal medial line of said board and the sides of said member inclining toward the longitudinal sides of said body portion, said member being interposed between the folds of the collar or collar band of the shirt folded about said board.

GEORGE FREDERICK HISS.
